(57) **CLAIM**

The ornamental design for a rear body of a golf car, as shown and described.

DESCRIPTION

FIG. 1 is a front perspective view of a rear body of a golf car; FIG. 2 is a front planar view thereof;

FIG. 3 is a rear view thereof;

FIG. 4 is a right side view thereof (the left side view being a mirror image of the right side); and,

FIG. 5 is a top view thereof.

The lines shown in phantom including the small apertures shown in FIGS. 1, 3, and 5 are for illustrative purposes only and do not form part of the invention.
